UNITED STATES PATENT OFFICE.

EVARISTE E. TALBOT, OF FALL RIVER, MASSACHUSETTS.

PARALLEL PICKER-STICK MOTION.

Application filed May 16, 1927. Serial No. 191,605.

The purpose of the parallel motion on a loom is to cause the picker to move in a direction as nearly as possible parallel to the race plate, since otherwise the picker in 5 travelling from one end of the box to the other would describe an arc of a circle in which it would occupy a higher position at the center of its movement than at its ends, thereby resulting in an unsatisfactory pick. 10 The ordinary parallel motion consists of a relatively stationary shoe having a level bearing face and a curved rocker to which the picker stick is fastened and which in turn rests upon the flat bearing face of the 15 shoe, being held in position by a projection on the shoe disposed in a slot cut in the rocker, thereby to allow the rocker to move freely as the picker stick swings back and forth. The curve of the rocker is such that 20 it forms the arc of a circle having the picker as its center and a radius equal to the distance between the picker and the shoe, so that as the picker stick swings back and forth on the rocker as a fulcrum, its upper end or 25 picker, is theoretically at least always maintained at the same level throughout its entire throw.

As a practical matter, however, the so-called parallel motion does not secure true 30 parallel motion of the picker stick at all points in its throw, due to a variety of factors which have long been recognized by loom builders.

According to my analysis of the problem, 35 the difficulty with the ordinary rocker type parallel motion is that it has itself an arcual motion which must be synchronized with the arcual motion of the picker stick. I have deliberately departed from the rocker type 40 parallel motion in my solution of the problem and instead I have interposed a novel compensating connection between the picker stick and the drive therefor effective to cause the picker end of the stick to move in a truly 45 horizontal plane at all points in its travel. My motion translating device is positive and reliable and results in a picker stick motion which may be described as truly parallel.

In the accompanying drawings I have 50 shown an embodiment of my invention which I have found satisfactory under actual conditions of use. In these drawings:

Figs. 1 and 2 are fragmentary elevations at the front of a loom of standard type 55 equipped with a parallel motion in accord-

ance with my invention, and showing the position of the parts when the picker stick is at either limit of its throw.

Fig. 3 is a detail view of my novel motion translating device removed. 60

Fig. 4 is a view similar to Fig. 3 but showing the device in an opposite position of operation.

Fig. 5 is a detail view of the spring box.

Fig. 6 is a section on the lines 6—6 of 65 Figs. 4 or 5, and

Fig. 7 is a view showing diagrammatically the truly parallel motion of the picker stick.

Although applicable to a variety of looms, I have shown my invention in these drawings as applied to a Northrop loom of the cone pick type drive for the picker stick. It will be understood, however, that this showing is purely illustrative and in no way limiting and that my device may be applied with 70 little or no modification to various other looms of standard type and standard picker stick drive. 75

In Figs. 1 and 2, I have illustrated sufficient of the picking motion of a cone pick type drive to make clear the construction and operation of my parallel motion. In these figures the numeral 1 indicates a part of the loom frame. The picking cam is indicated at 2, the cam shaft at 3, the cone on which the cam acts at 4 and the picking shaft at 5. Fastened to the opposite end of the picking shaft is the picking shaft arm 6, which carries a collar 7, to which is fastened a short lug strap 8, which is connected by the 80 lug stick 9 with another lug strap 10, fastened to the picker stick 11. 85

This picking motion is standard and forms no part of my invention. 90

In accordance with general practice, I position at the foot of the picker stick my parallel motion, which generally considered consists of the attachment detailed in Figs. 3 and 4. Such attachment comprises a relatively fixed plate or casting 12 which is 95 sleeved about one end of the usual rocker shaft 13 for the lay of the loom, as indicated at 14. The casting 12 is provided with an offset bearing 15 which is substantially vertically slotted, as indicated at 16, to receive 100 a pivot stud 17 adjustably held therein in any suitable manner. 105

Mounted on the stud 17 and slotted as at 18 to receive the stud is a strap 19 to which 110 the picker stick is fastened, as indicated at

20. At its lower end, the strap 19 is curved as shown and carries a stud 21. The stud 21 is disposed between two adjacent teeth of a ratchet wheel 22 which is formed as an integral part of a spring box 22 rotatably mounted on a shouldered stud 23 between the casting 12 and strap 19. Within the spring box and anchored to the stud 21 is the usual return spring 24 for moving the picker stick on its return motion.

In operation, the cone drive moves the picker stick in the direction indicated by the arrow A in Fig. 3 and the spring 24 returns the picker stick in the direction indicated by the arrow B. During the travel of the picker stick, however, the crank 21, 22, swings from the position shown in Fig. 1 to that shown in Fig. 2, so as to maintain the picker at the same horizontal level throughout its entire throw. This motion is in the nature of an eccentric motion and is indicated diagrammatically in Fig. 7 by the dotted and full line showing. Its effect is to cause the picker to travel in a substantially straight line throughout its entire throw, as seen in Fig. 7.

Various modifications in the construction and operation of my device may obviously be resorted to without departing from the spirit and scope of my invention, if within the limits of the appended claims.

What I therefore claim and desire to secure by Letters Patent is:

1. In a parallel picker stick motion, in combination with the usual picker stick drive, a relatively stationary casting mounted adjacent the foot of the picker stick, a crank carried by said casting, and a picker stick fastening member pivotally and slidably mounted on said casting and operatively connected with said crank for causing the

picker end of the stick to travel in a straight line throughout its entire throw.

2. In a parallel picker stick motion, in combination with the usual picker stick drive, a relatively stationary casting mounted adjacent the foot of the picker stick, said casting being substantially vertically slotted and having a crank, and a picker stick strap pivotally and slidably mounted in the slot of said casting and operatively connected with said crank to cause the picker end of the stick to travel in a straight line throughout its entire throw.

3. In a parallel picker stick motion, in combination with the usual picker stick drive, a relatively stationary casting mounted adjacent the foot of the picker stick, a shouldered stud carried by said casting, a spring box rotatably mounted on said stud and containing a ratchet and a return spring, and a picker stick strap pivotally and slidably connected between its ends to said casting and having a stud disposed between adjacent teeth of said ratchet and to which stud said return spring is anchored.

4. In a parallel picker stick motion, in combination with the usual picker stick drive, a relatively stationary casting mounted adjacent the foot of the picker stick, said casting being substantially vertically slotted, a shouldered stud carried by said casting, a spring box rotatably mounted on said stud and containing a ratchet and a return spring, and a picker stick strap pivotally and slidably mounted in the slot of said casting and having a stud disposed between adjacent teeth of said ratchet and to which stud said return spring is anchored.

In testimony whereof I affix my signature.

EVARISTE E. TALBOT.
